UNITED STATES PATENT OFFICE.

LOUIS E. LA CROIX, OF BALTIMORE, MARYLAND.

VENDING MACHINE.

Application filed November 14, 1925. Serial No. 69,064.

The present invention relates to vending machines.

An object of this invention is to overcome the difficulties heretofore encountered in the vending of bodies of irregular size and shape, and more particularly to provide a device which may be used in conjunction with a peanut roaster for dispensing desired quantities of the roasted peanuts in their shells upon the deposit of a coin of requisite value.

Another object of the invention is to provide a vending machine of this character with means for measuring out and delivering a quantity of peanuts and which also carries and singly feeds bags or like containers for the peanuts, and provides a combined bag support and outlet for controlling the final discharge of the measured quantity of the peanuts or like articles.

The invention further aims to provide a mechanism performing the above described functions, and which at the same time may be utilized for tripping or releasing motor driven machines or devices which may be used as a display or advertising accessory to the machine, such as to effect the operation of a display web or the playing of a graphophone or the like.

A still further object of the invention is to provide a measuring cup or receptacle which is adjustable as to quantity and which is so mounted that it may be moved vertically through a hopper or the like, such as is found in peanut roasting machines so that the freshly roasted peanuts may be vended directly from the roaster.

The above and various other objects and advantages of this invention will in part be described in and in part be understood from the following detailed description of the present preferred embodiment, the same being illustrated in the accompanying drawings, wherein:

Fig. 1 is a front elevation of a combined peanut roasting and vending machine constructed according to the present invention.

Fig. 2 is an enlarged fragmentary vertical section taken through the vending mechanism.

Fig. 3 is a transverse section taken through the same.

Fig. 4 is a horizontal section taken through the upper part of the vending machine.

Fig. 5 is a fragmentary perspective view

showing in detail the upper end of the measuring receptacle.

Fig. 6 is a fragmentary vertical section taken through the same.

Fig. 7 is an enlarged vertical section taken through the measuring receptacle on the line 7—7 of Fig. 6, and

Fig. 8 is a further enlarged vertical section taken through the measuring receptacle on the line 8—8 of Fig. 7.

Referring to the drawings 15 designates a casing which may be provided with a peanut roaster 16 of any approved form and beneath which is disposed a hopper 17 for receiving the peanuts when roasted, the hopper having a depending neck 18 at its central lower part through which the peanuts or other commodity may be withdrawn.

In the upper end of the casing 15 there may be mounted a web 19 or other device for displaying pictures, advertisements or the like used in promoting sales of the peanuts contained in the machine. The casing may of course be given any suitable configuration for housing the various devices employed.

Mounted to slide vertically in the neck 18 of the hopper or container is a receptacle 20 for measuring the quantity of peanuts. The receptacle 20 is given the same transverse configuration as that of the neck 18 so that the neck may serve as a guide and a support for the receptacle 20. The receptacle 20 has at its lower end a pair of outwardly extending fingers 21 which are disposed at opposite sides of the receptacle and are connected to belts 22 which are mounted upon and secured to the peripheral portions of wheels 23 fixed upon a shaft 24 which extends transversely in the casing 15 and has bearing therein at 25 at opposite ends.

When the wheels 23 are turned in one direction they raise the receptacle 20 upwardly through the neck into a position above the surface level of the nuts or other articles contained in the hopper 17. The weight of the receptacle is sufficient to turn the wheels 23 in a reverse direction when the wheels are released, and the upper end of the receptacle 20 is adapted to move down into the neck 18 below the bottom of the hopper 17 so that the contents of the hopper may flow toward and fill the upper end of the receptacle. The receptacle 20 is provided with an inner section or sleeve 26 which closely fits the inner wall of the receptacle and pro-

22

vided with adjusting pins 27 selectively engaged in openings 28 formed through the outer wall of the receptacle 20 to hold the sleeve 26 at the desired height within the receptacle. The openings 28 are vertically spaced apart and the spaces therebetween may be graduated to adjust the containing upper end portion of the receptacle 20 to definite measuring capacities. The sleeve 26 is provided upon its upper end with a shutter 29 providing a bottom for the measuring receptacle and the shutter 29 is mounted on hinges 30 and adapted to swing downwardly within the sleeve 26. The shutter 29 is supported across the upper end of the sleeve by a rod 31 which projects at its upper end through a notch or opening 32 formed in the edge of the shutter 29. The rod carries a spring finger 33 which engages beneath the shutter and which is curved so as to cam outwardly from beneath the shutter when the latter is lowered. The lower end of the rod 31 is loosely mounted in a horizontal bearing 34 carried upon the inner side of the receptacle 20 below the sleeve 26, the rod 31 being bent outwardly at right angles at its lower end for passage through the bearing 34 and the rod being held at its upper end inwardly toward the shutter 29 by a spring 35. The lower outer end of the rod 31 lies in the path of a trip finger 36 which projects inwardly from the casing 15 so as to strike the rod 31 when the receptacle 20 is raised and thus release the shutter or bottom 35 tom 29.

The shutter 29 also carries a rod 37 connected at its upper end by an eye 38 to the shutter. The rod 37 is carried downwardly through a slot 39 formed in the side of the receptacle 20 and also through the sleeve 26, the rod being carried down at the exterior of the receptacle to a point spaced below the same. When the rod 37 is forced upwardly it swings the shutter or bottom 29 into a raised position.

The shaft 24 is provided with a pulley 40 spaced from the wheels 23 and over which is secured a belt 41 having one end fixed to the pulley 40 and its other end attached 50 at 42 to a vertically movable actuating rod 43. The lower end of the rod 43 is slideable in a bracket 44 carried by the casing 15 and the upper end of the rod 43 has an outturned handle 45 thereon which projects through a 55 slot 46 formed in the front wall of the casing 15. The rod 43 is provided at an intermediate point with a stop sleeve 47 which may be secured thereto by a set screw or the like to obtain the desired adjustment and 60 which is adapted to engage at its upper and lower sides locking pawls 48 and 49 which are carried upon the opposite ends of a rocking lever 50 pivoted intermediate its ends on a stud 51 projecting inwardly from the 65 casing 15.

The upper pawl 48 is pivoted between its ends at 52 and the inner or heel end of the pawl is adapted to move upwardly against a depending stop shoulder 53 so that the outer end of the pawl 48 can not move below 70 a horizontal position. The pawl 49 is pivoted at 54 intermediate its ends and its inner end is adapted to engage an upwardly facing stop shoulder 55 carried upon the lower end of the lever 50 so that the pawl 49 can 75 not move upwardly beyond a horizontal position. These pawls 48 and 49 are adapted to hold the stop 47 and the rod 43 in either raised or lowered positions until the lever 50 is rocked for releasing the pawls from the 80 stop 47.

Arranged adjacent to the lever 50 is a coin chute 56 which opens through the front wall of the casing 15 for receiving coins and which is provided in one side with a slot 85 57 through which projects a detent 58 pivoted at 59 and adapted to be struck at its inner end by a coin 60 as the latter falls through the chute 56. The detent 58 has a heel portion 61 disposed at an angle to the detent 90 and which normally holds the detent upwardly in a slot 57 but which is adapted to be overbalanced by the coin 60 to raise the heel 61 against the lower end of the lever 95 50 to swing the latter inwardly toward the rod 43 so that when the rod is lowered, as shown in Fig. 2, it will be locked in such position until the lever 50 is swung in a reverse direction.

The lever 50 is relatively light and is 100 carefully balanced on its pivot 51 so that but light pressure is required for moving the lever back and forth.

The coin chute 56 opens into a coin box 62 or the like which is disposed in the lower 105 end of the casing 15.

The receptacle 20 carries upon its lower end a flexible neck or connecting portion 63 which opens at its upper end into the receptacle 20 and at its lower end opens 110 into a chute 64 which is of relatively broad construction at its upper end and which gradually converges at its lower end into a cylindrical nozzle which projects through a vertical slot 65 formed in the front wall 115 of the casing 15. The chute 64 is pivoted at 66 intermediate its ends in such position that the peanuts or the like are permitted to flow first into the pan 64 embodying the upper end of the chute and when the chute 120 is swung into the position shown in Fig. 3 the peanuts are permitted to flow downwardly into a bag 67 or the like which may be placed over the outer end of the chute. The chute carries upon its inner end a 125 curved finger 68 lying in the path of the rod 37 and adapted to engage the same to raise the rod and close the bottom 29 when the inner end of the chute is swung upwardly.

The shaft 24 carries a pulley 69 over 130

which is trained a belt 70 which also passes over a larger pulley 71 on a shaft 72 for turning shaft. The shaft however carries a ratchet wheel 73 which is engaged by a pawl 74 mounted on the pulley 71 for turning the shaft 72 in one direction only. The shaft 72 carries a transversely corrugated roller 75 of rubber or the like adapted to engage beneath a stack of bags, such as 67, to intermittently feed the bags from the bottom of the stack one at a time. The bags are partly supported upon a shelf 76 which is mounted on the front wall of the cabinet 15 and in line with the lower edge of a slot 77 through which the bags may be individually projected. The roller 75 is proportioned to partially advance the lowermost bag from the stack through the slot 77 so that the user may grasp the bag and withdraw it from the casing or cabinet.

The chute 64 pivotally carries one end of a pull rod 78 which extends to the lower end portion of the lever 50 and is provided with an elongated loop 79 engaging an eye 80 mounted on the lower end of the lever 50, the loop 79 being of sufficient length to permit the free inward movement of the lever 50 by the detent 58 without rocking the chute 64.

The operating rod 43 may be provided with a clamp 81 secured thereto and pivotally to a rod 82 which extends to a phonograph or the like for tripping the same when the rod 43 is lowered. The chute 64 is provided at its inner end with a laterally extending finger 83 adapted to trip a latch 84 carried by the casing 15 and which is provided with a rod 85 which extends to the advertising device 19 or the like for tripping the same for operation when the outer end of the chute 64 is lowered.

In operation, the receptacle 20 is adjusted to receive the desired amount of peanuts or the like in its upper end and is of sufficient weight to move downwardly into the bottom of the hopper 17 when the mechanism is released.

When a coin 60 is dropped in the chute 56 the coin strikes the detent 58 and rocks the lever 50 inwardly at its lower end. The handle 45 is now depressed to force the rod 43 downwardly and turn the wheel 40 and the shaft 24. This movement turns the wheels 23 and forces the receptacle 20 upward through the contents of the hopper 17 and carries a quantity of the peanuts or the like upwardly in the top of the receptacle. When the receptacle reaches its uppermost position the stop 36 strikes the rod 31 and moves the upper end of the rod outwardly in the notch 32 to release the bottom 29 when the contents of the measuring receptacle 20 fall downwardly through the receptacle and into the flexible neck 63 to the pan or upper end of the chute 64.

During the upward movement of the receptacle 20 the pulley 69 actuates the feed roller 75 to project a bag 67 outwardly through the casing. As the rod 43 reaches its lowermost position the stop 47 is tripped past the pawl 49 and is then locked beneath the pawl so that the weight of the receptacle 20 can not return the parts to normal position. The coin 60 passes the detent 58 and drops into the box 62. The bag 67 may be fitted over the lower end of the chute 64 and the said lower end depressed as shown in Fig. 3 so that the contents of the chute may freely slide down therethrough into the bag. At this time the arm 68 on the rear end of the chute 64 strikes the rod 37 and moves it upwardly to close the bottom 29 and to pull the rod 78 upwardly for swinging the lever 50 into a reverse position.

When the pawl 49 is pulled away from the stop 47 the receptacle is free to move downwardly and turn the wheels 23 and the shaft 24 back into their normal position. The rod 43 is thus raised and is tripped past the upper pawl 48 and the stop 47 is locked above the pawl so that the rod 43 can not be forced downwardly until a second coin is placed in the slot or chute 56. The pulley 71 is turned backwardly as the rod 43 is raised but the pawl 74 merely idles over the ratchet wheel 73 so as not to disturb the position of the bags in the stack.

It is of course understood that various changes and modifications may be made in the details of construction and design of the above specifically described embodiment of this invention without departing from the spirit thereof, such changes and modifications being restricted only by the scope of the following claims.

What is claimed is:

1. A vending machine comprising a vertically movable receptacle having a pivoted bottom, a vertically movable operating member connected to the receptacle for raising the same, coin controlled locking means for holding the operating member in position with the receptacle raised, dispensing means including a device for releasing the bottom of the receptacle upon upward movement of the latter, and means for releasing said operating member when the dispensing means is operated.

2. A vending machine comprising a container for articles to be vended, a measuring receptacle movable vertically through the bottom of the container, an operating member connected to the measuring receptacle for raising the same, coin controlled means for locking the operating member against movement and releasable by a coin, a second locking means controlled by a coin for locking the operating member subsequent to operation to maintain the measuring receptacle raised, means for releasing

the contents from the receptacle, and means for releasing said second locking means to permit the operating member to move back into a locked normal position.

3. A vending machine comprising a vertically movable measuring receptacle having a pivoted bottom, an operating member connected to the receptacle for raising the same when the member is depressed, locking means for holding the operating member in raised position and releasable by a coin, a second locking means adapted to be set by the coin for holding the operating member depressed, means for releasing said pivoted bottom upon raising of the receptacle, and means for actuating said second locking means for releasing the operating member to permit the receptacle to drop into normal position.

4. A vending machine comprising a vertically movable receptacle having a pivoted bottom, a shaft, a wheel on the shaft, a flexible element secured to the wheel and to the receptacle, a second wheel on the shaft, a flexible element secured to the second wheel and extending thereon in a direction opposite to that in which said flexible element extends from the first wheel, an operating member connected to the flexible element of the second wheel, a coin controlled locking means for holding the operating member from depression, a second locking means actuated by the tripping of the first locking means for holding the operating member depressed when lowered, and a pivoted dispensing chute arranged beneath the receptacle and operatively connected to the bottom thereof for subsequently releasing the second locking means to permit the receptacle returning the parts to normal position.

5. A vending machine comprising a vertically movable receptacle having a pivoted bottom, means for releasing the pivoted bottom upon upward movement of the receptacle, a vertically removable rod operatively connected to the receptacle for raising the same when the rod is depressed, a stop carried by the rod, a rocking lever pivoted adjacent to the rod and having oppositely acting pawls on opposite ends, a delivery chute arranged beneath the receptacle and connected to said rocking lever for swinging the same when the chute is raised into position to engage the upper pawl with said stop and hold the rod in raised position, and coin

actuated means for reversing the position of the lever to release the upper pawl from the stop and dispose the lower pawl in the path of the stop, said stop adapted to be interlocked with the lower pawl when the rod is depressed.

6. A vending machine comprising a vertically movable measuring receptacle having a releasable bottom, a delivery chute pivoted beneath the receptacle, means for releasing the bottom of the receptacle, a depressible member connected to the receptacle for raising the same and adapted to be raised by the receptacle when the member is released, a rocking locking member normally disposed in position to lock the depressible member in raised position, coin actuated means for shifting the position of the locking member to release the depressible member and subsequently hold the depressible member when depressed, and a connection between the locking member and the chute for returning the locking member to normal position when the chute is swung downwardly.

7. A vending machine comprising a vertically movable receptacle having a releasable bottom, operating means for raising the receptacle, coin releasable locking means for holding the operating means against operation and for subsequently holding the operating means in position to maintain the receptacle elevated, a delivery device connected to the locking means for returning the same to normal position when the delivery device is actuated, and means for releasing the bottom of the receptacle.

8. A vending machine comprising a vertically movable receptacle having a releasable bottom, a shaft, a connection between the shaft and the receptacle, an operating device connected to the shaft for turning the same and raising the receptacle when the operating device is depressed, shiftable locking means for the operating device to normally secure it in raised position and to hold it in lowered position, coin actuated shifting means for changing the locking means from its normal position, a delivery chute connected to the locking means for returning it to normal position when the chute is swung into a delivery position, and means for releasing the bottom of the receptacle upon raising of the latter.

LOUIS E. LA CROIX.
